UNITED STATES PATENT OFFICE.

GORDON H. TISDALE, HECTOR G. S. ANDERSON, AND EDWIN B. THORNHILL, OF HURLEY, NEW MEXICO.

GAP ADJUSTER FOR SPARK PLUGS.

Application filed March 14, 1922. Serial No. 543,801.

To all whom it may concern:

Be it known that we, GORDON H. TISDALE, HECTOR G. S. ANDERSON, and EDWIN B. THORNHILL, citizen of the United States, residing at Hurley, in the county of Grant and State of New Mexico, have invented a new and useful Gap Adjuster for Spark Plugs, of which the following is a specification.

10 This invention relates to means for adjusting or spacing the points or electrodes of spark plugs to give a spark gap of proper length, and the main object of the invention is to provide simple and cheap means for 15 this purpose which will enable quick and accurate adjustment of the points.

The accompanying drawings illustrate an embodiment of our invention; Fig. 1 being a plan view of the device and Fig. 2 a perspective view showing the device in position on a spark plug.

The device consists of a plate or member 1, formed of suitable material, such as metal, having therein a centering opening 2 and 25 a slot 3 adjacent said opening, the outer and inner edges 4 and 5 of said slot being formed as cams extending eccentrically with reference to opening 2. The eccentricity or inclination of the outer edge portion 4 with 30 reference to an arc (indicated by dotted line *a*) concentric with openings 2, is opposite or reverse to the inclination of the inner edge portion 5 with reference to an arc (indicated at *b*) concentric with such opening. 35 Opening 2 is adapted to fit on the center point of a spark plug, and slot 3 is adapted to receive the side point of the plug and to engage, by its cam edges 4 and 5, with said point to adjust the same.

40 The member 1 may be further provided

with a gage pin 9 extending across a notch 8 in the side of said member, and with a hole 7 for suspending or attaching the device to a hook, chain or other support.

The device may be used by placing it on 45 a spark plug, as shown in Fig. 2, with the opening 2 fitting the center point 12 of the spark plug 11, and the side point or electrode 13 of the spark plug extending in slot 3. By then turning 50 the device to the right, the cam face 4 may be caused to engage the point 13 to bend the same inwardly; or by turning the device to the left, the cam face 5 may be caused to engage the point 13 to bend 55 the same outwardly. In this manner the electrode or point 13 may be adjusted inwardly or outwardly as may be required to give the proper spacing. The gage pin 9 may be used to determine when the points 60 are properly spaced, by slipping it between such points.

The slot 10 in the edge of member 1 may be used to engage the point 13 and adjust it to a radial position with respect to the 65 center point 12 of the spark plug.

What we claim is:

A spark plug gap adjuster comprising a member having a centering opening adapted to fit on a spark plug point and provided 70 with a slot having portions reversely eccentric to such opening, and adapted to act as cam means for adjusting the other spark plug point inwardly or outwardly.

In testimony whereof we have hereunto 75 subscribed our names this 1st day of March, 1922.

GORDON H. TISDALE.
HECTOR G. S. ANDERSON.
EDWIN B. THORNHILL.
